UNITED STATES PATENT OFFICE

WILLIAM LEMBKE, OF AMSTERDAM, NEW YORK, ASSIGNOR, BY MESNE ASSIGNMENTS,
TO BIGELOW-SANFORD CARPET CO., INC., A CORPORATION OF MASSACHUSETTS

PILE RUG AND PROCESS OF MAKING THE SAME

Application filed September 27, 1928. Serial No. 308,808.

The present invention relates to a process of making rugs of the tapestry type having a pile surface and a bordered design and to an incomplete rug made by such process. An object of the invention is to provide for making pile surfaced tapestry rugs with bordered designs with less labor and at less cost. Another object of the invention is to reduce the labor required in coloring the pile-forming 10 yarns of pile-surfaced tapestry rugs having end border designs.

To these and other ends, the invention consists of certain parts and combinations of parts, all of which will be hereinafter described: the novel features being pointed out in the appended claims.

In the drawings:

Fig. 1 is a plan view of two pile-surfaced tapestry rugs made in accordance with this 20 invention; and

Fig. 2 is a diagram of a section of one of the rugs showing the manner in which the pile-forming yarn is looped between repeated designs.

Tapestry rugs are formed generally by chain warps and transverse shots or weft threads interlocking with the chain warps and also with the pile-forming yarns providing the pile surface of the rugs.

Heretofore in making these rugs it has been customary to color the pile-forming yarns for the complete length of the rug to be woven, or, in other words, each pile-forming yarn has a color combination for the entire length of each plurality of rugs. This has two disadvantages; first, it requires a coloring device of a size to color or print the pile-forming yarns for the entire length of a rug to be formed, and, second, for rugs of different lengths, yarn coloring or printing devices of different sizes are required.

According to this invention, the size of the yarn coloring or printing device is reduced so that the labor of producing such coloring or printing device is less and rugs of various lengths may be woven from yarn colored or printed by one yarn printing or coloring device.

In carrying out this invention, a design is 50 selected for the rug having its portion $x-z$

intermediate the end border portions $a-b$, $c-d$, comprising duplicate or repeated portions $x-y$, $y-z$ while maintaining a symmetrical design.

A printing or coloring device is now made in the usual manner to color the pile forming yarn for producing the end borders $a-b$ and $c-d$ and a single intermediate repeatable portion $x-y$ or $y-z$ (both being the same). This coloring device is now employed for coloring a drum of yarn from which a plurality of rugs can be made, the yarn on the drum being colored so that the yarn for producing each single repeatable portions $x-y$ or $y-z$ will be separated from the others by the colored yarn for producing the two portions $a-b$ and $c-d$, or in other words, the colored portions for producing each two portions $a-b$ and $c-d$ will be spaced from like portions and will be separated by colored portions for producing only one of the repeatable designs $x-y$ or $y-z$. The pile forming yarn is woven in rugs on a tapestry loom of any suitable construction. The border portion $a-b$ is first woven, then the portion $x-y$ is woven. When the portion $x-y$ is completed the pile forming yarn beam or drum is turned so as to produce a loop e in each yarn on the drum, this loop taking up or eliminating from the rugs that portion of the yarn which would produce a portion $c-d$ and $a-b$. The weaving is then continued and the portion $y-z$, a repetition of the portion $x-y$, and the portion $c-d$, is woven to produce a complete rug. This is continued until the yarn on the beam or drum is completely used. If a longer rug is desired, the repeatable portion ($x-y$ or $y-z$) is repeated any desired number of times, the portions $c-d$ and $a-b$ being eliminated each time preferably by looping the yarn and the portions $c-d$ being woven when the desired length of rug is obtained. After the rug is completed, the looped portions e are cut substantially at the pile surface and are invisible in the completed rug.

What I claim as my invention and desire to secure by Letters Patent is:

1. A method of making bordered pile-surfaced tapestry rugs with a repeated design intermediate end border designs which com- 100

prise coloring the pile-forming yarn from which a plurality of rugs is produced at spaced portions so that from each of such spaced portions the pile surface of two end border designs of opposite ends of two rugs may be produced, coloring those portions of the pile-forming yarn between each two end border design-forming portions with a single design to be repeated in the intermediate portions of the rugs, weaving the pile-forming yarn into rugs, and during such weaving, eliminating some of those portions colored to produce the pile surfaces of two border designs of two adjacent rugs so that the intermediate design is repeated in the intermediate portions of the rug whereby a complete continuous body between the end borders is produced.

2. A method of making bordered pile-surfaced tapestry rugs with a repeated design intermediate end border designs which comprise coloring the pile-forming yarn from which a plurality of rugs is produced at spaced portions so that from each of such spaced portions the pile surface of two end border designs of opposite ends of two rugs may be produced, coloring those portions of the pile-forming yarn between each two end border design-forming portions with a single design to be repeated in the intermediate portions of the rugs, weaving the pile-forming yarn into rugs, and during such weaving, forming loops from some of those portions colored to produce the pile surfaces of two border designs of two adjacent rugs so that the intermediate design is repeated in the intermediate portions of the rug, and cutting off the loops whereby a complete continuous body between the end borders is produced.

3. An incomplete bordered pile-surfaced tapestry rug having end border designs and a repeated design intermediate the end border designs, said rug having loops in the pile-forming yarn between the repeated intermediate designs, colored the same as those portions of the pile forming yarn that produced the end border designs and projecting beyond the surface of the rug.

WILLIAM LEMBKE.
